UNITED STATES PATENT OFFICE.

ARTHUR K. BECKWITH, OF DOWAGIAC, MICHIGAN, ASSIGNOR TO ESTATE OF P. D. BECKWITH, INCORPORATED, OF DOWAGIAC, MICHIGAN.

JOINT FOR STOVES OR FURNACES.

1,035,144.

Specification of Letters Patent. Patented Aug. 13, 1912.

Application filed November 11, 1911. Serial No. 659,706.

To all whom it may concern:

Be it known that I, ARTHUR K. BECKWITH, a citizen of the United States, residing at the city of Dowagiac, county of Cass, 5 and State of Michigan, have invented certain new and useful Improvements in Joints for Stoves or Furnaces, of which the following is a specification.

This invention relates to improvements in 10 joints for stoves or furnaces.

The main objects of this invention are to provide an improved joint in which the parts to be joined can be readily formed as 15 castings and one in which the joint is so formed that the packing or cement is easily inserted in assembling the parts and when the parts are assembled, is positively retained.

Further objects, and objects relating to 20 structural details, will definitely appear from the detailed description to follow.

I accomplish the objects of my invention by the devices and means described in the following specification.

25 The invention is clearly defined and pointed out in the claims.

A structure which is a preferred embodiment of my invention is clearly illustrated in the accompanying drawing, forming a 30 part of this specification, in which:

Figure I is a detail perspective view of a cook stove structure embodying the features of my invention. Fig. II is a detail vertical section taken on a line corresponding 35 to line 2—2 of Fig. I. Fig. III is a detail elevation looking from the left of Fig. II.

In the drawing, similar reference numerals refer to similar parts in all the views.

Referring to the drawing, 1 represents the 40 top plate of a cook stove or range, and 2, a side plate or wall thereof. The wall or plate 2 is arranged with its edge abutting the under side of the plate 1 within the flange 3. The flange 3 is inclined inwardly, 45 its inner face or wall 4 being at an angle to the side of the wall 2. The edge of the flange 3 rests against the side of the plate 2, there being a wedge-shaped space between the flange and the plate 2 for the reception 50 of the cement 5. The flange forms a bead-like finish for the plate 1 and is provided with downwardly projecting ears 6 for the

attaching bolts 7. The cement space of the joint being wedge-shaped, it is quite impossible for the cement to fall out in use and 55 at the same time, the parts can be readily cast and are easily assembled. In assembling the parts, the cement is placed in the flange, the plate 2 positioned and drawn into place by the bolts. This compacts the 60 cement and causes it to fill the joint space throughout, making an effective tight joint.

I have illustrated my improvements adapted to the joint between the top plate and side wall of a cooking stove but it will 65 be obvious that it can be readily adapted for other relations such as for the joints of furnaces.

Having thus described my invention, what I claim is new and desire to secure by 70 Letters Patent is:

1. In a joint for stoves or furnaces, the combination with a top plate formed with a downwardly and inwardly projecting flange, a side plate arranged on the inner side of 75 said flange with its outer side against the edge of the flange and its upper edge abutting the under side of the top plate, there being a wedge-shaped space between the said flange and the side plate for the reception 80 of cement, said flange being provided with attaching ears, and a clamping bolt arranged through said ears to clamp the side plate against the edge of the flange.

2. In a joint for stoves or furnaces, the 85 combination of a plate formed with an inclined joint flange thereon, a second plate arranged on the inner side of the flange with its outer side against the edge of the flange and with its upper edge abutting the 90 flange plate on the inner side of its said flange, there being a wedge-shaped space between the flange and said second plate, a packing material arranged in said space, and means for clamping said second plate 95 against the edge of said flange and against the packing material in said space.

In witness whereof, I have hereunto set my hand and seal in the presence of two witnesses.

ARTHUR K. BECKWITH. [L. S.]
